CLAIM

We claim the ornamental design for a headlight, as shown and described.

DESCRIPTION

FIG. 1 is an upper front left-side perspective view of a headlight according to a first embodiment of the design;

FIG. 2 is a rear view thereof;

FIG. 3 is a left-side view thereof;

FIG. 4 is a bottom view thereof;

FIG. 5 is a front view thereof;

FIG. 6 is a top view thereof;

FIG. 7 is a right-side view thereof; and

FIG. 8 is a lower back left-side perspective view thereof.

FIG. 9 is an upper front left-side perspective view of a headlight according to a second embodiment of the design;

FIG. 10 is a rear view thereof;

FIG. 11 is a left-side view thereof;

FIG. 12 is a bottom view thereof;

FIG. 13 is a front view thereof;

FIG. 14 is a top view thereof;

FIG. 15 is a right-side view thereof; and

FIG. 16 is a lower back right-side perspective view thereof.

FIG. 17 is an upper front left-side perspective view of a headlight according to a third embodiment of the design;

FIG. 18 is a rear view thereof;

FIG. 19 is a left-side view thereof;

FIG. 20 is a bottom view thereof;

FIG. 21 is a front view thereof;

FIG. 22 is a top view thereof;

FIG. 23 is a right-side view thereof; and

FIG. 24 is a lower back left-side perspective view thereof.

The broken lines illustrate portions of the headlight that form no part of the claimed design.
